UNITED STATES PATENT OFFICE

JOHN P. MONSON, OF ANN ARBOR, MICHIGAN

OSCILLATING SANDER

Application filed July 7, 1930. Serial No. 466,156.

The present invention pertains to a novel rotary sanding machine of the type having an oscillating sanding tool.

The primary object of the present invention is to devise a sanding machine having a work supporting table to which the work may be fixed, the table being designed to rotate and tilt to any desired angle to permit the work to be moved by the table into contact with the tool. This feature constitutes a decided improvement over the conventional type of sanding machines in which the work is held by the hand of the operator, making accurate surfacing an operation of the greatest skill and which is obviously not fool proof for any slip by the operator might bring his hands in contact with the tool. In other words the present device is equipped with means giving a greater safety factor than was heretofore possible.

Another object of the present invention is to provide a novel sanding machine having a rotatable and tiltable work supporting table mounted and operated in combination with a novel tool driving mechanism. The rotary driving mechanism is designed to cause oscillation and rotation of the sanding drum mounted upon the upper end thereof and is constructed so that all the moving parts may be enclosed in a casing in such a manner that they may be adequately lubricated by being submerged in a bath of oil. The oscillation as well as the rotation gives a smoother and more satisfactory surface on the work by preventing grooving and at the same time increases the useful life of the sanding drum by evenly distributing the wear thereon.

With the above and other ends in view the invention consists in the matters hereinafter set forth and more particularly pointed out in the appended claims, reference being had to the accompanying drawings, in which

Figure 1 is a front elevation of the present machine;

Fig. 2 is a side elevation of the machine with the work supporting table broken away and in cross section;

Fig. 3 is an enlarged cross sectional view of a fragment of the machine taken on the

line 3—3 of Fig. 1 and illustrating the driving mechanism in detail;

Fig. 4 is a cross sectional view taken substantially along the line 4—4 of Fig. 1, the adapter and the sanding drum being shown in top plan;

Fig. 5 is a cross sectional detail taken on the line 5—5 of Fig. 2;

Fig. 6 is a cross sectional detail taken on the line 6—6 of Fig. 3;

Fig. 7 is a side elevation illustrating the table clamping and indexing mechanism;

Fig. 8 is a side elevation of one of the table supporting members, and

Fig. 9 is a side elevation of the member which slidably supports the entire table supporting mechanism.

Like characters are employed throughout to designate the corresponding parts.

The numeral 1 indicates a base which may be formed of an enlarged solid piece of metal or may be of the type which may be secured permanently to the floor. An upright post 2 is secured in the base and has a head 3 attached to the upper end thereof, the head being provided with a table-like upper surface having ways 4 formed thereon. Slidable upon the head 3 and guided by the ways 4 is mounted a stirrup member 5, a side elevation of which is shown in Fig. 9. The stirrup member is provided with a screw-threaded bore 6 in which is received a set screw 7 to engage the ways 4 to prevent movement of the stirrup on the head after the adjustment of the former has been made. To assist in this adjustment there is provided a suitably graduated scale 9 on the stirrup which cooperates with the indicating finger 10 on the head 3.

The outer ends of the stirrup member 5 are provided with bores 11 and with downwardly projecting arms 12 in which are formed bores 13. The stirrup is designed to support the split ring 14 having the bores 15 which correspond with the bores 6 in the stirrup so that bolts may be passed through both sets of said bores to mount the ring 14 inside the stirrup. The ring is provided with a pair of downwardly projecting curved arms 16 having the curved slots 17 to accommodate

set screws 18 which are passed through the bores 13 in the stirrup member's arms 12.

From the above description it becomes apparent that the ring 14 is tiltably mounted upon the stirrup 5 which is in turn slidably mounted upon the upright post 2. The ring 14 supports the work supporting table 19 which is provided with a central bore 20 having a downwardly projecting flange 21 which 10 is received in the ring 14. The ring 14 is split as before mentioned and is provided with ears 22 having bores 23 through which a set screw 24 is passed to tighten the ring around the flange 21. The set-screw 23 may be 15 tightened to provide a snug fit for the flange 21 in the ring 14 to permit rotation of the table or it may be tightened to such an extent that rotation of the table may be prevented if such may be desired. A suitable 20 work clamping member 25 is secured in conventional ways 26 formed upon the upper face of the work supporting table.

Around the upper portion of the bore 20 in the table is provided a counter bore 27 which 25 receives a flange 28 formed on an adapter 29 which is inserted in the bore 20. The purpose of the adapter is to permit the table to have a comparatively large sized bore which 30 will accommodate sanding drums of various diameters but it becomes apparent that if a small sanding drum were used with a large bore 20 that it would be impossible to sand small pieces of work. Therefore this invention accommodates adapters of standard outer dimensions having elongated slots to accommodate drums of various sizes while the work supporting table is at various angles relative to the grinding drum.

To indicate the angularity of the work supporting table there is provided a graduated plate 63 secured to the bottom of the curved arm 16 on the ring 14, an indicating arm 64 being carried by the arm 12 on the member 5 to cooperate therewith. For supporting 45 the table in a horizontal plane there is provided an adjustable screw 62, carried by the member 5 and projecting upwardly to provide a positive stop for the table as it tilts in its ring support which is pivotally mounted 50 in the stirrup member 5.

A plate 30 is provided with arms 31 to partly surround the post 2 and straps 32 are secured to these arms to firmly attach the plate to the post. To the plate 30 is secured a 55 casing 33 having suitable packing 34 at both top and bottom and having bearings and bearing races as indicated by the numeral 35. The packing in the upper end of the casing is spaced on either side of the bearings and this portion of the casing is provided with a lubricating fitting 36, the necessity for special lubrication at this point becoming apparent as the description progresses. The lower portion of the casing is filled with lubricant by 60 means of the lubricating fitting 37.

A sanding drum 38 is mounted upon the upper end of the shaft 39 having an enlarged portion 40 journaled in a bracket 41 formed on the inside of said casing. The portion 40 is provided with a central bore 42 provided with a keyway 43 in which is mounted a key 44. The key 44 engages in a slot formed in the shaft 45 supported by the bearing races 35 and by additional bearings 46 mounted in a bracket 47 formed on the inside of said casing. The lower end of the shaft 45 projects beneath the casing and is connected as at 48 to an electric motor 49 secured by bolts 50 upon the plate 30.

Mounted upon the shaft 45 and spaced by 50 spacers 51 between the bracket 47 and the bottom of the casing is the worm 52, keyed to rotate with said shaft. The worm 52 meshes with a worm gear 53 which is keyed to a shaft 54 mounted in brackets 55 formed on the inside of the bottom of said casing. Wheels 56 are secured upon the outer ends of said shaft 54 and are provided with bolts 57 for attaching links 58 to said wheels in a concentric manner whereby the wheels serve as cranks 59 forcing said links upwardly and downwardly.

The upper ends of said links are pivotally attached as at 59 to a ring 60 which surrounds the shaft 39 and butts against the upper end 65 of the enlarged portion 40 against which it is held by a securing ring 61. Therefore, when the shaft 45 is rotated by the motor 49 the drum upon the upper end of the shaft is also rotated by connection established by the key 44 and the bore 42. Rotation of the shaft 45 also causes rotation of the worm gear 53, causing rotation of the shaft 54 and thereby causing the links 58 to successively raise and lower the shaft 39 by means of the ring 60 which is secured to the shaft. The upward and downward movement causes oscillation of the sanding drum on the shaft 39 while the rotary driving connection remains established due to the manner in which the shaft 45 projects into the bore 42.

Although a specific embodiment of the present invention has been illustrated and described it is to be understood that various changes may be made within the scope of the appended claims without departing from the spirit of the invention and such changes are contemplated.

What I claim is:

1. The combination with a sanding drum, 120 of means for rotating and oscillating said drum, and a rotatable work supporting table mounted upon a tiltably and slidably support in a manner whereby said sanding drum extends through an opening in said table. 125

2. The combination with a sanding drum, 130 of means for rotating and oscillating said drum, a rotatable work supporting table having an opening therein through which said sanding drum extends and mounted upon a 135

tiltable and slidable support, and means for clamping work upon said table.

3. The combination with a sanding drum having means for rotating and oscillating the same, of a table having an opening therein through which said sanding drum extends and adapted to support work in contact with said drum, said table being adapted to slide longitudinally, to tilt angularly and to rotate relative to said sanding drum.

4. The combination with a sanding drum having means for rotating and oscillating the same, of a table having an opening therein through which said sanding drum extends and adapted to support work in contact with said drum, said table being adapted to slide longitudinally, to tilt angularly and to rotate relative to said sanding drum, and means for clamping work upon said table.

20 5. The combination with a sanding drum of means for rotating and oscillating said drum, and means for mounting a work supporting table with said drum projecting therethrough, said table being adapted to slide longitudinally, to tilt angularly and to rotate relative to said sanding drum.

6. A sanding machine comprising a vertical post supported by a suitable base, a head having guiding ways mounted upon the upper end of said post, a stirrup member slidable in said ways on said head, a ring pivotally mounted in said stirrup, a work supporting table supported in said ring, a sanding drum projecting through said work supporting table, and means for oscillating and rotating said drum.

7. A sanding machine comprising a vertical post supported by a suitable base, a head having guiding ways mounted upon the upper end of said post, a stirrup member slidable in said ways on said head, a ring pivotally mounted in said stirrup, a work supporting table supported in said ring, clamping means for securing work upon said table, a sanding drum projecting through said work supporting table, and means for oscillating and rotating said drum.

8. The combination with a work supporting table adapted to be adjusted by rotary, longitudinal and angular movement, a motor driven telescopic shaft, a sanding drum mounted upon the upper end of said shaft, and means actuated by the rotation of the lower portion of said telescopic shaft for causing oscillation of the upper portion carrying the sanding drum.

9. The combination with a work supporting table adapted to be adjusted by rotary, longitudinal and angular movement, of a lubricant containing casing mounted adjacent said table, a motor driven telescopic shaft mounted in said casing, a sanding drum mounted upon the upper portion of said shaft, and means actuated by rotation of the lower portion of said telescopic shaft

for causing oscillation of the upper portion carrying the sanding drum.

10. A sanding machine comprising a vertical post supported by a suitable base, a head having guiding ways mounted upon the upper end of said post, a stirrup member slidable in said ways on said head, a ring pivotally mounted in said stirrup, a work supporting table supported in said ring, a motor driven telescopic shaft supported by said post, a sanding drum mounted upon the upper portion of said shaft, and means actuated by rotation of the lower portion of said shaft for causing oscillation of the upper portion.

In testimony whereof I affix my signature.
